WASTE RECEPTACLE

Ralph E. Weimer, Lombard, Ill., assignor to McDonald's
System, Inc., a corporation of Illinois

Filed Aug. 22, 1966, Ser. No. 3,554

Term of patent 14 years

(Cl. D58—17)

FIG. 1

FIG. 2

FIG. 3

FIGURE 1 is a front perspective view of a waste receptacle showing my new design;

FIGURE 2 is a rear perspective view thereof; and

FIGURE 3 is a side elevational view of an upper portion of the waste receptacle.

The ornamental design of this application is characterized by the upswung and extended hood assembly, in which the hood assembly projects well beyond the vertical projection of the lower waste receiving portion, the base of the forwardly extending portion angling upwardly to the front of the hood assembly and inverted V-shaped decorative flutes as, for example, seen in FIGURE 3 extending upwardly and forwardly of the lower waste receiving portion.

I claim:

The ornamental design for a waste receptacle, substantially as shown and described.
